UNITED STATES PATENT OFFICE

HARRY ELLWOOD SLOAN, OF PITMAN, NEW JERSEY

LOCKING DEVICE FOR FUDGE MANDRELS

Application filed September 1, 1928. Serial No. 303,395.

This invention, stated in its broadest terms, relates to printing presses and has more especial relation to means for securing a fudge type turtle or quick or late news device to the fudge mandrel.

- In practice a mandrel is arranged to contain one or more fudges, type turtles, or quick or late news devices, as they are called. For explanation purposes, the term "fudges" will 10 be employed. These fudges in practice have been held in place by a movable head or nut upon one end of the mandrel. According to this practice the head or nut is loosened sufficiently to become disengaged from the 15 fudges so that the latter may be removed from the mandrel. In the connection it is to be noted that with the release of one fudge, all the fudges which may be upon the mandrel are simultaneously released. 20 This is a bad feature because it is not always desirable to remove all of the fudges at one time, and further the screwing and unscrewing of the head or nut with a socket wrench as now practiced takes considerable time. 25 Again, the changing of fudges according to the practice above described often results in press starting with the fudges loose on the mandrel with resultant damage to the fudges, blankets, and other parts. 30 The leading object of the present invention is to overcome the above described disadvantages and provide a fudge mandrel having a fixed head and individual locking devices for the fudges associated with the 35 head.

A further object of the present invention is to provide a construction of the character stated whereby there is materially reduced the time for removing a fudge or fudges 40 which is an important item in newspaper work to which this invention is particularly adapted.

A further object of the present invention is to provide a construction of the character 45 stated in which a maximum degree of safety is provided in the individual locking of fudges.

A further object of the present invention is to provide a device of the character stated 50 which is simple in structure, efficient in use,

and which may be inexpensively manufactured and employed upon press mandrels now in use.

A still further object of the present invention is to provide a device of the character 55 stated in which the mandrel head is fixed and in which end-wise shiftable and cushioned individual clamping means are provided for operation by a removable handle.

Other and further objects of the present 60 invention reside in the provision of general details of construction and in the arrangement and combination of parts for attaining the results sought by the foregoing objects. 65

The invention consists of the novel construction hereinafter described and finally claimed.

The nature, characteristic features and scope of the invention will be more fully understood from the following description taken in connection with the accompanying drawings forming part hereof, and in which:

Fig. 1, is a view of a fudge mandrel having a head and its parts thereon embodying the 75 invention.

Fig. 2, is a view in end elevation of Fig. 1.

Fig. 3, is a view, drawn upon an enlarged scale, in longitudinal section of certain of the parts shown at the right hand side of Fig. 1; 80 and

Fig. 4, is a top or plan view of Fig. 3.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged 85 and organized, and that my invention is not limited to the precise arrangement and organization of the instrumentalities as herein shown and described.

Referring now to the drawings in detail, the reference numeral 1 designates a conventional fudge mandrel exteriorly screw threaded at one end as at 3. In practice this mandrel is of hollow formation. Peripherally considered the mandrel is provided with a 90 95 100

series of pins designated 4, the purpose of which will presently appear. Having threaded relation with the screw threaded part 3 of the mandrel is a head 5, shown as being cylindrical in shape. This head 3 is locked with respect to the mandrel proper by means of a pin or set screw 6. Seated within and arranged around the head 5 in concentric relation therewith are a plurality of endwise shiftable plungers 7, bevelled upon their under faces as at 8, and movable through the counter-sunk portions 9 of the fixed head 5. These end-wise shiftable plungers are arranged in pairs, see Fig. 2, one pair being arranged to lock a single fudge, as will herein-after appear.

As each pair of plungers and companion parts are of duplicate structure, a description of one pair will suffice.

Extended from each of a pair of end-wise shiftable plungers is a longitudinally disposed rod 10, see Fig. 3, movable through a longitudinal opening in the fixed head 5 and each rod is provided at its outer end with a reduced portion 11 which passes through an aperture in head 5. The fixed head 5 is provided with a shoulder 12 for each opening through which the rod 10 passes, and a spiral spring is interposed between each shoulder 13 and the inner end of an endwise shiftable plunger 7. In order to prevent these end-wise shiftable plungers 7 and their rods 10 from moving about their horizontal axes each plunger 7 is provided with a fixed pin 13 movable in a longitudinal groove 14 in the fixed head 5. Spanning a pair of end-wise shiftable rods 10 is an arched plate 15 which is loosely mounted upon the reduced ends 11 of said rods. Each plate is prevented from displacement from a rod 10 by means of castellated nuts 16 and cotter pins 17, the nuts engaging the screw-threaded, reduced parts 11 of rods 10.

The reference numeral 18 designates a fudge or the like, one or more of which are employed in practice upon a mandrel, the mandrel shown being equipped to hold six fudges in the present case. One end of a fudge abuts against an annular flange (not shown) of the fudge mandrel, as is well understood in the art. The opposite end of a conventional fudge is somewhat tapered at 19, and centrally apertured as at 20. In positioning a fudge upon the mandrel the apertured portion 20 thereof is fitted over a pin 4, previously referred to, upon the mandrel. The pins 4 serve as positioning and steadyng parts for the fudges. With a fudge thus positioned the pair of spring impelled plungers which have been manually shifted to the right in Fig. 3, are released and force their bevelled faces 8 against the bevelled face 19 of the fudge. This provides a very practical, efficient and convenient locking device for fudge mandrels and also provides a device which

may be very quickly operated. To release a fudge use is made of a handle 22 having a bevelled face 23. In practice the bevelled face 23 of the tool 22 is inserted between the outer face of the fixed head 5 and the inner face of a plate 15 and the handle 22 forced or wedged inwardly between the plate and the fixed head, thus causing the end-wise shiftable plungers to move outwardly against the action of the springs 25 and clear the bevelled part 19 of the fudge.

From the foregoing description it is obvious that the above described locking device may be employed for the very quick removal of fudges from a fudge mandrel, and that because each fudge is individually locked to place upon a mandrel little or no danger is present of the press being started with loose fudges upon the mandrel as has heretofore been the custom. Heretofore the end of a fudge was clamped by a screw passing through opening 20 and constant screwing and unscrewing of screws to center a fudge resulted in the screw threads in the mandrel wearing out and a plug introduced and re-threaded. By use of the fixed aligning or centering pins 4, as at present employed, this disadvantage is overcome and much time is saved.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

What I claim is:

1. In combination a rotary fudge mandrel, a head fixed to said mandrel, a fudge including a base plate, means for detachably clamping said fudge upon said mandrel, said means including a spring pressed plunger carried by said head, the inner end of said plunger overlying the fudge base plate in clamped position of said fudge, means for moving said plunger end-wise out of engagement with the fudge, and longitudinally shiftable spring pressed means for retracting said plunger.

2. In combination a rotary fudge mandrel, a head fixed to said mandrel, a fudge including a base plate, means for detachably clamping said fudge upon said mandrel, said means including a pair of connected and spaced spring pressed plungers carried by said head, the inner ends of said plungers overlying the fudge base plate in clamped position of said fudge, means for moving said plungers end-wise out of engagement with the fudge, and longitudinally shiftable spring pressed means for retracting said plunger.

3. In combination a rotary fudge mandrel, a head fixed to said mandrel, a fudge includ-

ing a base plate, means for detachably clamping said fudge upon said mandrel, said means including a spring-pressed plunger carried by said head, the inner end of said plunger having a bevelled portion for overlying and engaging a similar part of the fudge base plate, means for moving said plunger end-wise out of engagement with the fudge, and longitudinally shiftable spring pressed

10 means for retracting said plunger.

4. In combination a rotary fudge mandrel, a head fixed to said mandrel, a fudge including a base plate, means rotative with the head but non-rotative about its longitudinal axes
 15 for detachably clamping said fudge upon said mandrel, said means including a spring-pressed plunger carried by said head, the inner end of said plunger overlying the fudge base plate in clamped position of said fudge,
 20 means for moving said plunger end-wise out of engagement with the fudge, and longitudinally shiftable spring pressed means for retracting said plunger.

5. The combination of a rotary mandrel, a
 25 fudge including its complemental bevelled base plate positioned on said mandrel, a head fixed to and rotatable with the mandrel, a plunger the inner end thereof having a bevelled under face carried by said head and
 30 movable into engagement with the fudge base plate with the bevelled part of the plunger overlying the bevelled part of the fudge base plate in clamped position of said fudge, a spring for pressing said plunger toward the
 35 mandrel, and means for retracting the plunger.

6. The combination of a rotary mandrel, a fudge including its complemental base plate positioned on said mandrel, a head rotatable
 40 with the mandrel, a plunger carried by said head and movable into engagement with the fudge base plate in clamped position of said fudge with the plunger overlying one end of the fudge, a spring for pressing said
 45 plunger toward the mandrel, a plate detachably carried by said plunger, said plate being arranged with respect to said head for insertion of a tool between said plate and the outer face of the head for retracting the
 50 plunger.

7. The combination of a rotary mandrel, a fudge arranged upon the mandrel, a fixed pin upon the mandrel to center said fudge, a head rotatable with the mandrel, a pair
 55 of radially disposed spring-pressed plungers arranged opposite the fudge and movable into engagement with the fudge with the free ends of the plungers overlying the fudge, and means for moving said plungers away
 60 from said fudge.

8. In combination a rotary mandrel, a fudge arranged thereon, means fixed upon the circumference of said mandrel to center said fudge, a head fixed to said mandrel and
 65 longitudinally bored to receive a pair of

plungers, each plunger having a bevelled face at one end and a stem projected from its other end, a spring to maintain said plungers in engagement with a fudge, and a plate spanning a pair of stems, said plate being arranged with respect to said head for the insertion of a tool between the opposed faces of said head and plate for causing retraction of the plunger.

9. In combination a fudge mandrel, a
 70 fudge arranged thereon, a head fixed to said mandrel and longitudinally bored to receive a pair of plungers, each plunger having a bevelled face at one end and a stem projected from its other end, a spring to maintain said plungers in engagement with a fudge, a plate spanning a pair of stems, said plate being arranged with respect to said head for reception of a tool between the opposed faces of said head and plate for causing retraction
 75 of the plunger.
